CLAIM

I claim the ornamental design for an aerodynamic wheel for a motor vehicle, as shown and described.

DESCRIPTION

FIG. 1 is a perspective view of the wheel embodying the new design;

FIG. 2 is a bottom view thereof;

FIG. 3 is a side view thereof;

FIG. 4 is a cross-sectional view through line 4-4 of FIG. 2; and,

FIG. 5 is a plan view of the wheel embodying the new design.

FIGS. 1-5 show features of a wheel in broken lines. These features are shown for environmental purposes and do not form any part of the claimed design. The broken lines immediately adjacent the solid line portions of the design form the boundary of the design, with the broken lines forming no part of the claimed design.
